UNITED STATES PATENT OFFICE.

HORACE FALK NEUMEYER, OF MACUNGIE, PENNSYLVANIA, AND JONAS FRANCIS YOUNG, OF NIAGARA FALLS, NEW YORK.

WASTE-VALVE FOR WATER AND STEAM PIPING SYSTEMS.

SPECIFICATION forming part of Letters Patent No. 586,779, dated July 20, 1897.

Application filed August 18, 1896. Serial No. 603,127. (No model.)

To all whom it may concern:

Be it known that we, HORACE FALK NEUMEYER, residing at Macungie, in the county of Lehigh and State of Pennsylvania, and JONAS FRANCIS YOUNG, residing at Niagara Falls, in the county of Niagara and State of New York, citizens of the United States, have invented a new and useful Waste-Valve for Water and Steam Piping Systems, of which the following is a specification.

This invention relates to waste-valves for use in connection with water and steam piping systems; and it has for its object to provide a new and useful valve of this character especially well adapted for use in connection with hydrants, whereby the service pipe or pipes can be automatically drained of surplus or standing water therein, which is of considerable importance in cold weather to prevent freezing and the consequent annoyances.

With these and other objects in view, which will readily appear as the nature of the invention is better understood, the same consists in the novel construction, combination, and arrangement of parts hereinafter more fully described, illustrated, and claimed.

In the drawings, Figure 1 is a vertical longitudinal sectional view of a waste-valve constructed in accordance with this invention and shown in its normal position for draining surplus water in a hydrant or piping thereabove. Fig. 2 is a similar view on the line 2 2 of Fig. 1, showing the valve closed to permit a free passage of liquid therethrough without waste or escape thereof. Fig. 3 is a similar view to Fig. 2, showing a modified form of valve without the use of springs. Fig. 4 is a sectional view of the valve, showing an arrangement of the parts to adapt the valve for use in connection with steam-pipes for draining from such pipes the water of condensation after live steam is cut off.

Referring to the accompanying drawings, the numeral 1 designates a valve-casing preferably made in sections and comprising the separate casing-sections 2 and 3, the casing-section 2 being interiorly threaded at one end, as at 4, to receive the reduced exteriorly-threaded neck 5 of the section 3, but the casing may be formed of one casting, so that the

sections 2 and 3 will form integral parts of the casing, as clearly illustrated in Fig. 3 of the drawings. The valve-casing 1 is provided at its opposite ends with the interiorly-threaded coupling-necks 6, adapted to have fitted therein the threaded ends of the pipe-sections 7, of the line of piping in connection with which the valve is used for the purpose of draining surplus or standing water in the piping above the valve.

The construction of valve illustrated in Figs. 1, 2, and 3 of the drawings is especially designed for use in connection with hydrants, and in this case the pipe-section 7, fitted in the lower end of the valve-casing, is joined with or leads from the ordinary hydrant-valve, which is opened and closed in the usual way to control the flow of water, and in this adaptation of the waste-valve the pipe-section 7, fitted in the upper end of the valve-casing, forms a part of the hydrant and leads to the discharge-spout thereof, so with this explanation it is believed that the arrangement of the valve in the line of piping will be understood.

Referring particularly to Figs. 1 and 2 of the drawings, the valve-casing 1 is provided intermediate of its ends with an interior annular valve-seat 8, below or at one side of which the valve-casing is formed with a cylindrical guide-bore 9, while above or at the opposite side of the valve-seat 8 the casing is provided with an enlarged valve-chamber 10, directly above which and within the outlet or delivery neck of the casing the latter is provided with a transversely-arranged waste pipe or passage 11, opening at its opposite ends, as at 12, at the outside of the valve-casing and provided centrally between said open ends 12 and in one side with a drain-port 13, through which the surplus or standing water above the valve is designed to pass into the pipe or passage 11 and thence to the exterior of the valve-casing 1.

The transversely-arranged waste-pipe 11 is sufficiently small in diameter so as not to interfere with the free flow of water through the outlet coupling-neck of the valve-casing, and arranged to play within the enlarged valve-chamber 10, below the waste-pipe 11,

is a hollow cylindrical plunger-cup 14. The hollow cylindrical plunger-cup 14 is slidably mounted to work in the cylindrical guide-bore 9 of the valve-casing, and is provided 5 with a closed end 15, having an annular valve-shoulder 16, adapted to work onto the interior valve-seat 8 when the plunger-cup is in its normal closed position. The closed end 15 of the plunger-cup 14 is further provided 10 with small relief openings or perforations 17 and with a central pin-opening 18, adapted to slidably receive therein a movable valve-pin 19, provided with a disk head 20 at one end, which works below the closed end 15 of the plunger-cup, and opposite its disk head 20 the said valve-pin 19 is provided with a point 21, adapted to seat itself in the drain-port 13 of the pipe 11. A pin-adjusting spring 22 is coiled on the valve-pin 19 and is connected at one end to such pin and bears at its other end against the closed end 15 of the plunger-cup, so as to normally project the pointed end of the pin beyond the closed end of the plunger-cup and in close proximity to 15 the drain-port 13 in alignment therewith. The said plunger-cup is further provided in diametrically opposite sides between its ends with the enlarged side ports 23, which are sufficiently large to permit a free flow of the 20 liquid therethrough and thereby not decrease the volume of water passing through the pipes connected with the valve-casing.

Assuming the construction described to be used in connection with hydrants, the parts 35 of the valve normally assume the positions illustrated in Fig. 1, but when the hydrant-valve is opened the water enters at the lower end of the valve-casing and passes into the hollow plunger-cup 14. The pressure of the 40 water raises the plunger-cup and carries the point of the valve-pin into the drain-port 13 to close such port immediately in advance of the ports 23 being uncovered by passing above the interior valve-seat 8. The pressure of the 45 water continues to elevate the hollow plunger-cup until the ports 23 are completely uncovered to allow the water to freely pass through the line of piping and the valve-casing to the point of use without escaping through the 50 drain-pipe 11 of the valve-casing, it being understood that while the water is passing through the valve-casing there can be no waste, because the pressure against the hollow plunger-cup is constant and keeps the 55 valve-pin seated in the drain-port of the waste-pipe. When the water is shut off, the weight of the column of water above the valve, with the aid of the spring 22, instantly forces down the plunger-cup, and it in turn engages with 60 the disk head 20 of the valve-pin and draws the point of said pin out of the drain-port 13, thereby allowing all the water above the valve to escape through said drain-port and the waste-pipe. When the supply of water is 65 cut off and the plunger-cup is closed onto its valve-seat 8, the small relief openings or per-

forations 17 allow the water to quickly pass through the same, so as to reduce the resistance offered to the quick closing of the plunger-cup and the consequent uncovering of the 70 drain-port 13, as will be readily understood by those skilled in the art.

In Fig. 3 of the drawings is illustrated a modification of the valve in which the use of a spring in connection with the valve-pin and the plunger-cup is entirely dispensed with, and in this modification of the invention the valve-pin 19 is provided directly adjacent to its point 21 with a stop-collar 25, adapted to engage with the upper side of the closed end 80 of the plunger-cup to limit the downward movement of the valve-pin when it is uncovering the drain-port and to hold said valve-pin in a proper position. In addition to being provided with the collar 25 the valve-pin 85 19 in the modification referred to is provided at its lower end with an enlarged disk head 26, which is of a diameter substantially agreeing with the internal diameter of the plunger-cup, so as to form a piston loosely working 90 within said plunger-cup, and when the collar 25 of the valve-pin 19 rests against the closed end of the plunger either in its elevated or lowest position the periphery of the disk head 26 should project slightly below the upper 95 edges of the side openings 23 of the valve-casing.

In the modified construction just described the water on being admitted to the hollow plunger-cup first impacts itself against the 100 disk or piston head 26 of the valve-pin and immediately forces the point of the valve-pin into the drain-port 13, so as to close such port, and after this operation occurs the pin remains stationary while the pressure of the 105 water forces the hollow plunger up to a height sufficient to uncover the enlarged side ports 23 and allow the free and uninterrupted passage of the liquid or water through the valve-casing.

In the construction referred to the operation of the valve is positive, and no matter how slight the pressure of the water may be the waste-pipe will be closed first, so that no water can escape until the hydrant is shut off, 110 and, furthermore, should the valve controlling the inlet of water into the casing 1 of the waste-valve fail to operate at any time for any reason the defect will be immediately known, as the automatic waste-valve will be instantly 115 closed, and water instead of wasting into the ground will fill up the hydrant and attract attention by wasting out of the spout.

The preferred forms of the invention and the manner of using the same have been described; but when the valve is used for the purpose of draining water of condensation from steam-pipes after the live steam is cut off it is necessary to place the valve below the steam-pipe and invert the parts, as illustrated 125 in Fig. 4 of the drawings. In this arrangement of the valve it is necessary to provide 130

for normally holding the plunger-cup closed on its seat 8, and to provide for this a spring 27 is interposed between the closed end of the cup and the shoulder of the casing, formed at 5 one side of the waste-pipe 11. While the movable valve-pin 19 might be employed in connection with the plunger-cup when supported by the spring 27, such plunger-cup may be provided at its closed end with a fixed 10 valve-point 19^a, adapted to seat itself in the drain-port 13 and subserve the same function as the valve-pin 19, hereinbefore fully referred to.

The operation of the construction illustrated in Fig. 4 is in all respects similar to the operation of the valve described in connection with Figs. 1, 2, and 3, and at this point it will be noted that while in Figs. 1 and 2, and also in Fig. 3, no spring is necessary for 15 the closing of the plunger-cup onto its seat still a spring similar to the spring 27 may be employed to insure this operation, and various changes in the form, proportion, and the minor details of construction may be resorted to without departing from the principle or 20 sacrificing any of the advantages of this invention.

Having thus described the invention, what is claimed, and desired to be secured by Letters Patent, is—

1. In a waste-valve, the valve-casing provided at a point near one end with a transverse waste pipe or passage open at both ends and provided intermediate of its ends in one 5 side with a drain-port communicating with the interior of the casing, and a pressure-operated plunger-cup guided for movement within the casing and carrying a valve-point adapted to seat itself in said drain-port, substantially as set forth.

2. In a waste-valve, the valve-casing provided with a waste-pipe having an interiorly-arranged drain-port, a pressure-operated plunger-cup guided for movement within the 5 valve-casing, and an independently-movable valve-pin slidably mounted in the closed end of the plunger-cup, substantially as set forth.

3. In a waste-valve, the casing having an interior guide-bore, and a waste-pipe having an interiorly-arranged drain-port, and a hollow plunger-cup sliding in said guide-bore and provided with a closed end carrying a valve-point and having therein small relief-openings, said plunger-cup being further pro-

vided with enlarged side ports covered and 55 uncovered by the movement of the cup in said guide-bore, substantially as set forth.

4. In a waste-valve, the valve-casing having an interior enlarged valve-chamber, a guide-bore at one side of said valve-chamber, 60 and a waste-pipe having an interiorly-arranged drain-port, and a hollow plunger-cup sliding in said guide-bore and provided with a closed end carrying a valve-point adapted to cover and uncover said drain-port, said 65 plunger-cup being further provided with enlarged side ports adapted to be covered and uncovered by the movement of the cup in said guide-bore, substantially as set forth.

5. In a waste-valve, the valve-casing having an interior enlarged valve-chamber, a guide-bore at one side of said chamber, and a waste-pipe having an interiorly-arranged drain-port, a hollow plunger-cup sliding in 70 said guide-bore and provided with a closed end and with enlarged side ports, and a movable valve-pin loosely mounted in the closed end of the plunger-cup and provided at one end with a point adapted to seat itself in said drain-port, substantially as set forth. 75

6. In a waste-valve, the valve-casing having an interior annular valve-seat, an enlarged valve-chamber above the valve-seat, a cylindrical guide-bore below the valve-seat and a transverse waste-pipe open at both ends 80 and provided with a central drain-port, a hollow cylindrical plunger-cup sliding in said guide-bore and provided with a closed end having an annular valve-shoulder and small relief-openings, said plunger-cup being further provided with enlarged side ports, a valve-pin slidably mounted in the closed end 85 of the plunger-cup and provided at one end within the cup with a disk head and at its opposite end with a point adapted to seat itself in said drain-port, and a spring coiled on and connected to the valve-pin at one side of the closed end of the plunger-cup, substantially as set forth. 90

In testimony that we claim the foregoing as 95 our own we have hereto affixed our signatures in the presence of two witnesses.
